CLAIM

The ornamental design for an articulating blade assembly for hair removal device, as shown and described.

DESCRIPTION

FIG. 1 is a front perspective view of an articulating blade assembly for hair removal device of the present invention showing our new design;

FIG. 2 is a front view thereof;

FIG. 3 is a back view thereof;

FIG. 4 is a side view thereof;

FIG. 5 is a top plan view thereof; and,

FIG. 6 is a bottom plan view thereof.

The broken lines in the figures are for the purpose of illustrating portions of the articulating blade assembly for hair removal device, which form no part of the claimed design.
